HOUSING FOR A PORTABLE FOOD MIXER

Downer P. Dykes, Lawrence, Kans., assignor to Rival
Manufacturing Company, Kansas City, Mo.

Filed Sept. 14, 1970, Ser. No. 24,966

Term of patent 14 years

Int. Cl. D7—04

U.S. Cl. D44—1

FIG. 1 is a side elevational view of a housing for a portable food mixer showing my new design;

FIG. 2 is a top plan view thereof;

FIG. 3 is a bottom plan view thereof;

FIG. 4 is an end elevational view taken of the left hand end of FIG. 1; and

FIG. 5 is an end elevational view taken of the right hand end of FIG. 1.

I claim:

The ornamental design for a housing for a portable food mixer, as shown and described.
